(57) **CLAIM**

The ornamental design for a computer, as shown and described.

DESCRIPTION

FIG. 1 is a perspective view of a first embodiment of a computer showing our new design;

FIG. 2 is a front elevational view thereof;

FIG. 3 is a rear elevational view thereof;

FIG. 4 is a right side view thereof;

FIG. 5 is a top plan elevational view thereof;

FIG. 6 is a bottom plan view thereof; and

FIG. 7 is an enlarged partial perspective view cut along the lines 7—7 and 7'—7' of FIG. 1.

FIG. 8 is a perspective view of a second embodiment of a computer showing our new design;

FIG. 9 is a front elevational view thereof;

FIG. 10 is a rear elevational view thereof;

FIG. 11 is a right side view thereof;

FIG. 12 is a top plan elevational view thereof;

FIG. 13 is a bottom plan view thereof; and

FIG. 14 is an enlarged partial perspective view cut along the lines 14—14 and 14'—14' of FIG. 8.

FIG. 15 is a perspective view of a third embodiment of a computer showing our new design;

FIG. 16 is a front elevational view thereof;

FIG. 17 is a rear elevational view thereof;

FIG. 18 is a right side view thereof;

FIG. 19 is a top plan elevational view thereof;

FIG. 20 is a bottom plan view thereof; and,

FIG. 21 is an enlarged partial perspective view cut along the lines 21—21 and 21'—21' of FIG. 15.

Dot-dash broken lines define the boundaries of, but not included in, the claimed design.

The evenly-spaced broken lines in the drawings illustrate unclaimed portions of the computer and form no part of the claimed design.
